SIGNAL FLAG

Robert White, East Braintree, Mass.

BEST AVAILABLE COPY

Filed June 7, 1962, Ser. No. 70,462

Term of patent 3½ years

(Cl. D72—1)

FIG. 1

FIG. 2

FIG. 1 is a view in elevation of a signal flag showing my new design, and

FIG. 2 is an enlarged perspective view of one of the clamping elements to better illustrate configurational details thereof.

The back of the flag is conventional, and in the drawing portions are lined to indicate color contrast rather than any specific color. The flag has no substantial thickness.

The essential features of the design reside in alternate white and colored bands converging downwardly from the longitudinal edges of the flag and separated at their inner

ends by a white longitudinal band containing the word BREAKDOWN in block letters.

I claim:

The ornamental design for a signal flag, substantially as shown and described.
